HAFTUNG, OF KIEL, GERMANY, A FIRM.

VIBRATION AMPLIFIER.

Application filed October 24, 1922, Serial No. 598,648, and in Germany September 18, 1922.

The object of the invention is to provide an improved vibration amplifier of the microphone-telephone-type, i. e. of the type in which a microphone is actuated by vibrations of the mechanical vibratory structure or system of a telephone connected to a telephone line.

Generally speaking, the invention resides in certain improvements in the acoustic relations of the vibratory parts of the electromagnetic or the electrodynamic unit of the telephone and of the microphone, and in certain improvements in the balancing of the electrical circuits.

We shall now describe our invention in detail with reference to the accompanying drawings.

In said drawings:

Fig. 1 shows a vibration amplifier in which the telephone is of the electromagnetic type;

Fig. 2 shows diagrammatically the acoustic relations of the mechanically vibratory parts of the electromagnet and the microphone of Figure 1; and

Fig. 3 shows a vibration amplifier in which the telephone is of the electrodynamic type.

In the amplifier shown in Fig. 1, the armature 1 carried by a diaphragm 3, and the magnetic field 6 together with the alternating current coil 7, represent the telephone system. The armature and field magnet are preferably formed of steel sheets in order to diminish the ordinary iron losses as much as possible.

The two poles of the U-shaped magnet converge towards its central axis. In consequence of this it becomes possible to use a smaller and thicker armature than usual in cooperation with a normal sized U-magnet. Such an armature is more advantageous because it has a smaller magnetic resistance than the usual long and flat armature of the ordinary U-magnet without having a larger mass.

The electromagnet is rigidly seated in a recess in a coupling member 4. The diaphragm 3 which carries the armature 1 is also attached to member 4, so that it acts as an elastic connection between the armature 1 and the member 4, permitting vibratory

movement of the armature toward and away from the electromagnet.

The microphone is located in a recess in coupling member 4 at a point opposite the recess carrying the electromagnet. One electrode 8 of the microphone is rigidly seated in member 4, although of course insulated therefrom; while the other electrode 11 is carried by the diaphragm 10, and insulated therefrom by layer 13. The space between the electrodes 8 and 11 is filled with carbon granules 12, retained by retaining ring 9 of yielding insulating material such as felt or the like. The diaphragm 10 is secured at its periphery to the member 4, thus permitting vibratory movement of the electrode 11 toward and away from electrode 8.

It is to be mentioned that the elastic force of the diaphragm 10 should preferably be great compared to the inherent elastic force of the volume of granulated carbon 12, because the latter in consequence of its variability causes the natural frequency of the mechanical vibratory structure represented by the microphone to vary. As a rule, the elastic force of the diaphragm should be at least three quarters of the entire elastic force of the mechanical vibratory structure represented by the microphone.

It is sometimes desirable to increase the damping of the mechanically vibratory structures or system of the apparatus. This may be accomplished by means of very shallow or flat air chambers or spaces, such as 23 and 24, preferably formed by the rigid plates 25 and 26 respectively provided with small apertures 27. The air within chambers 23 and 24 is caused by the vibrations of the diaphragms 3 and 10 to pass back and forth through the small apertures or openings, thus causing friction and a damping of the diaphragms.

The microphone-telephone-system of the amplifier is hung by means of rubber cords 22 within a casing 21, being insulated by these cords against mechanical disturbances. The electrodes of the microphone and the terminals of the alternating current coil are electrically connected to plugs attached to the wall of the casing 21. In this way an amplifier element is furnished, which may

easily be changed or replaced, similar to the well known vacuum tube amplifiers.

A locking or securing device 29 serves to protect the apparatus within the casing 21 from damage by shocks when it is not in use. To lock the apparatus in the casing the lock pin 30 is pushed down through guide sleeve or tube 33 to engage the apparatus and press it down toward block 31. When the pin 30 is pushed down so that the pin 32 projecting laterally therefrom is below the lower edge of sleeve 33, the pin 30 is turned in the sleeve, thus moving pin 32 into locked position against the lower edge of sleeve 33.

15 We have found it advantageous to counterbalance the self-induction of the alternating current coil 7 by means of a capacity. Such a capacity is represented by the condenser C_1 . Similarly the self-induction of the amplifier 20 telephone 17 may be counterbalanced by another condenser C_2 .

Such a condenser, as for instance the condenser C_1 , together with the alternating current coil 7, is an electrical oscillatory circuit 25 of a definite natural frequency. If the natural frequency of a mechanical vibratory structure of the amplifying apparatus is equal or about equal to that of this electric oscillatory circuit, a multiple resonant system 30 arises consisting of the electrical circuit and the mechanical structure.

With regard to the fact that a condenser in the circuit of the coil 7 has the purpose of counterbalancing the self-induction of this coil, and with further regard to the fact that the value of this self-induction is greatest at a frequency of excitation lying a little below the frequency of resonance of the mechanical vibratory structure of the telephone system 35 of the amplifier, it is to be preferred not to equalize exactly the natural frequencies of this mechanical structure and the oscillatory circuit but to tune the latter to a pitch corresponding to the frequency at which the 40 self-induction of the coil is the greatest.

Another feature of the invention referring to the cooperation of an amplifier of the described kind with a given telephone line consists in the alternating current resistance of 50 the line and the alternating current resistance of the alternating current coil being equalized as far as possible. In this way the efficiency of an amplifier plant of this kind may be enhanced to a remarkable extent. If 55 the resistance of the line or of the combination of apparatus in which the amplifier is to be used is known beforehand it can be considered in manufacturing the amplifier itself by the resistance of the alternating current coil of the amplifier being proportioned to the alternating current resistance of the 60 plant.

As to the acoustic features of the present invention, the apparatus of Fig. 1 embodies 65 two mechanically tuned vibratory structures.

Each structure is made up of two masses connected by an elastic member. One of the structures is formed essentially of the armature 1 as one mass; the electro-magnet 6, the coil 7, and a portion of member 4, as the other mass; and the diaphragm 3 as the elastic connecting member. The other of the structures is formed essentially of the electrode 11 as one mass; the electrode 8, and a portion of member 4, as the other mass; and the diaphragm 10 as the elastic connecting member. It will be seen from this that the member 4 acts as a mass common to both vibratory structures and couples them together.

80 The acoustic relations just mentioned are illustrated diagrammatically in Fig. 2. In this figure, the two vibratory structures are designated as I and II. One structure is composed of mass m_3 , a portion of common mass m_2 , and elastic connecting member e_2 ; the other structure is composed of mass m_1 , a portion of common mass m_2 , and elastic connecting member e_1 . The designations m_1 , m_2 , m_3 , e_1 , and e_2 , have been applied to Figure 1 on the drawings for the sake of clarity. According to the invention the two structures are each individually tuned to the same or nearly the same frequency and are then coupled together, with a result substantially analogous to that produced when two tuned electrical circuits are coupled together, in that a biresonant system is obtained, that is the resonance curve of the coupled system has two peaks. In a coupled acoustic system such as shown in Fig. 2, the closeness or looseness of coupling depends upon the ratio between the common mass and the other masses. We have found it advantageous in the apparatus shown to have the common mass at least ten times as great as either of the other two masses. Furthermore, the relative magnitudes of the masses determine the relative amplitudes of vibrations of the masses, so that it is possible to attain a different amplitude of vibration acting upon the microphone from that acting at the electro-magnet.

105 The modification of the invention shown in Fig. 3 differs from Fig. 1 in that the armature of the electromagnet is replaced by a coil 18 which moves back and forth in the air space of a pot-shaped magnet having a central pole piece 19.

110 What we claim is:—

1. In apparatus of the character described, an electromagnet and an armature elastically connected together to form a tuned vibratory structure, and a microphone having its two electrodes elastically connected together to 115 form a second tuned vibratory structure, the two vibratory structures being coupled together acoustically by means of a common mass, and the masses of the two vibratory structures being proportioned to secure 120

125

130

larger amplitudes of vibration acting on the microphone than acting at the electromagnet.

2. A vibration amplifier unit comprising a vibration amplifier element of the microphone-telephone-type with a magnetic field; a casing, enclosing the amplifier element; elastic holders carrying the element within the casing; and a locking device securing the element within the casing when not used.

3. A vibration amplifier unit comprising a vibration amplifier element of the microphone-telephone-type with a magnetic field; a casing enclosing the amplifier element;

15 elastic holders carrying the element within the casing; and a locking device consisting of a stop pin.

4. In an apparatus of the character described a substantial, common mass including an electromagnet, an armature for said electromagnet elastically connected to said common mass and a microphone elastically connected to said common mass, whereby said armature and said microphone are 25 acoustically coupled by said common mass.

5. A vibration amplifier of the microphone telephone type comprising a substantial common mass including an electromagnet, an armature for said electromagnet elastically connected to said common mass and a microphone having two electrodes, the space between which is filled with granulated carbon and means having a large elastic force 30 as compared with the elastic force represented by the granulated carbon for coupling acoustically said microphone to said common mass.

6. In a vibration amplifier of the microphone telephone type, the combination comprising two mechanical vibratory structures coupled together by a common mass, one of said structures comprising an armature mounted upon an elastic member and an electromagnet forming a part of said common mass and operating said armature, the other 45 mechanical vibratory structure comprising the common mass including an electrode and a second electrode mounted upon an elastic member and coupled acoustically to said common mass, the common mass being relatively large compared with the free masses.

7. In a vibration amplifier of the microphone telephone type the combination comprising two mechanical vibratory structures coupled together by a common mass, one of 55 said structures comprising an armature mounted upon an elastic member and an electromagnet forming a part of said common mass and operating said armature, the other mechanical vibratory structure comprising the common mass including an electrode and a second electrode mounted upon an elastic member, and coupled acoustically to said common mass, the common mass being at least ten times as large as one of the 60 free masses and the free masses being about equal.

In testimony whereof we affix our signatures.
